UNITED STATES PATENT OFFICE.

EDWARD A. STEWART, OF DAYTON, OHIO.

ROTARY ENGINE.

1,332,367.

Specification of Letters Patent.

Patented Mar. 2, 1920.

Application filed May 14, 1919. Serial No. 296,979.

To all whom it may concern:

Be it known that I, EDWARD A. STEWART, a citizen of the United States, residing at Dayton, in the county of Montgomery and 5 State of Ohio, have invented certain new and useful Improvements in Rotary Engines, of which the following is a specification.

The invention comprises a compound rotary engine employing a two-fold motive agent, to-wit, oil and steam. The oil in its explosive condition acts by the force of its impact upon the buckets of one piston to drive the same, and steam generated through 10 the heat due to said explosions, acts by the force of its impact upon the buckets of a second piston to concurrently drive it, the two pistons being mounted in separate communicating cylinders.

20 The object of the invention is to provide a rotary engine of maximum efficiency and power through the structural characteristics hereinafter described and claimed.

Referring in general terms to the accompanying drawings, Figure 1 is a rear elevation of the engine. Fig. 2 is a section thereof on line 2—2 of Fig. 1. Fig. 3 is a section on the line 3—3 of Fig. 2. Fig. 4 is a section on line 4—4 of Fig. 2. Fig. 5 is a 25 detail view of the starting gear. Fig. 6 is a detail sectional view of the water inlet valve. Fig. 7 is a sectional view of the air and oil inlet valve. Fig. 8 is a section on line 8—8 of Fig. 7. Fig. 9 is a bottom plan 30 view of the above mentioned valve. Fig. 10 is a section on the line 10—10 of Fig. 3.

Referring more particularly to the drawings, 1 represents a base which supports a casing 2 through the agency of posts 3 as shown in Figs. 1, 2 and 3. The casing 2 is provided with a division wall 4 and end cover plates 5 and 6. The plates 5 and 6 are provided with bearings 7 in which is journaled a shaft 8 having a pulley 8^a. 40 Mounted on the shaft 8 and within the casing 2 are two rotors 9 and 10 separated by the division wall 4. The rotor 9 is actuated by the explosive effect of air and oil; while the rotor 10 is actuated by the expansive effect of steam as generated by water and the exhaust gases from the rotor 9. The rotor 9 is provided with pockets 11 having curved faces 12 which receive the impinging effect of explosive gases in chambers 13 in 45 the casing 2. The explosive gases are di-

rected against the curved faces 12 by passageways 14, and the passage of the gases is controlled by valves 15 slidingly mounted on grids 16. The valves 15 are provided with stems 17 which project out through the 50 cover-plate 5, and are moved in one direction by springs 18 mounted on the stems 17. The valves 15 are moved in the other direction by levers 19 pivoted at 20 and rocked by a cam race 21 in a drum 22 55 mounted on the shaft 8. The valves 15 are opened immediately after the explosions occur in the chambers 13. The air and oil is introduced into the chambers 13 through oil and air valves shown in detail in Figs. 7 60 and 8. The oil and air valves are provided with casings 23 mounted on the cover plate 5 and provided with central chambers 24 into which the air and oil are introduced 65 under high pressure. The admission of the 70 air and oil into the chambers 13 is controlled by valve-heads 25 mounted on stems 26 which extend out of the casing 23 through glands 27. On their outer ends, the stems 26 are provided with heads 28 which rest in 75 T slots in wedges 29 slidingly mounted on spring-controlled plungers 30. The spring-controlled plungers 30 maintain the valve-heads 28 normally closed. The wedges 29 are instrumental in regulating the amount 80 of air and oil introduced into the chambers 13 and are engaged by levers 31 pivoted at 85 32, and actuated by a cam race 33 in the drum 22. See Fig. 2. The position of the wedges relative to the heads 28 of the stems 90 26 determine the extent of the opening movement of the valve-heads 28, and consequently the amount of air and oil admitted to the chambers 13. The wedges 29 are connected by means of links 34 to levers 35 95 pivoted at 36 to the cover-plate 5. See Fig. 1. The levers 35 are connected by means of links 37, to an oscillating spider 38 mounted on the bearing 7 of the cover-plate 5. The spider 38 is provided with a handle 39 by 100 means of which the wedges 29 may be manually shifted. The arm 39 is attached to an oscillating plate 40 also mounted on the bearing 7 through the agency of a slotted link 41 and a bolt 42. The plate 40 is connected to a governor (not shown) which is instrumental in automatically shifting the wedges 29. The slotted link connection 41 is provided to permit the wedges 29 to be 105 manually shifted without disturbing the 110

governor. The air and oil valves are supplied with air and oil through individual pipes 43 and 44 which are connected to the casings 23 by means of bosses 45 and 46 (see Fig. 8). The individual pipes 43 and 44 are connected to headers 47 and 48 which receive the air and gas from a suitable source of supply through pipes 49 and 50 (see Fig. 5).
10 The air and oil are introduced into the chambers 13 at such a pressure that the oil ignites as soon as it comes in contact with the air and is properly diffused. To diffuse the mixture, the discharge opening of the valve is serrated as at 51 as is shown in Fig. 9. After the explosive gases impinge against the faces 12 of the pockets 11 they exhaust through passageways 52 into exhaust chambers 53 in the casing 2. The 15 entrance of the exhaust gases into the chambers 53 is controlled by valves 54 which slide on grids 55. The valves 54 are provided with stems 56 which extend out through the casing, and said valves are actuated by springs 57 and by levers 58 pivoted at 59 and actuated by the cam race 21. The 20 exhaust gases when they enter the chambers 53 possess a high degree of heat, and to utilize this energy, water is introduced into the chambers 53 which is converted into steam and the expansive action of which is utilized in connection with the rotor 10. The water is introduced into the chambers 53 through valves such as are 25 shown in section in Fig. 6. The water valves are provided with castings 60 attached to the cover-plate 5. Within the casings 60 are valve heads 61 mounted on stems 62 extending out of the casings 60 through glands 63. The 30 valve heads 61 are actuated by springs 64 and levers 65 pivoted at 66 and actuated by the cam race 33. The chambers 53 extend entirely across the casing 2 from the cover-plate 5 to the cover-plate 6, and are 35 adapted to transmit the steam to the rotor 10. The rotor 10 is provided with pockets 67 having curved faces 68 similar to the pockets 11. See Fig. 4. The steam from the chambers 53 is conducted to the pockets 67 through passageways 69 in the casing 2. The 40 passage of the steam out of the chambers 53 is controlled by valves 70 sliding on grids 71 and provided with stems 72 which extend through the cover-plate 6. The 45 valves 70 are actuated by the stems 72, levers 73 pivoted at 74, connecting rods 75, levers 76 pivoted at 77 and a cam race 78 in the drum 22. The steam and the products of 50 combustion exhaust out of the pockets 67 through passageways 80 in the casing 2 which lead to chambers 81. The chambers 81 in casing 2 are connected by means of tubes 112 with an exhaust pan 82 of any suitable construction, mounted on the shaft 55 8. The pan 82 is instrumental in creating a

partial vacuum at the exhaust, thereby adding to the efficiency of the engine.

The rotors 9 and 10 are provided with lateral and peripheral packing rods 83 and 84 which are instrumental in sealing the 70 pockets 11 and 67. The casing 2 adjacent to the rotor 9 is provided with a water circulating space 85 while the rotor itself is provided with a circulating space 86. The spaces 85 and 86 are instrumental in maintaining the engine at a suitable temperature and thereby protect the same from the high degree of heat generated by the explosions. The space 85 is provided with inlet and outlet pipes 87 and 88 (see Fig. 3). The space 80 86 is supplied with the cooling medium by pipes 90 and 91 (see Fig. 2) which are connected to the ends of the shaft 8 which is hollow and is connected with the space 85 through passageways 92 and 93. 85

The water for the generation of steam is supplied to the valves 60 through individual pipes or tubes 94 which lead from a header 95. See Figs. 1 and 5. The pipes 94 are provided with valves 96 having arms 97. 90 The said arms are connected by means of removable pins 98, to a lever 99 through the agency of a rod 100. The lever 99 is pivoted at 101 to a frame 102 supported by the casing 2. The removable pins 98 permit the 95 two lowermost valves 96 to be operated independent of the upper valves 96. The lever 99 is provided with a radial slot 103 and is connected to a lever 104 through the agency of the slot and a bolt 105. The lever 104 100 is also pivoted at 101 and is provided with a latch 106 in operative relation with a notched segment 107. The individual air and oil pipes 43 and 44 are provided with valves 108 having arms 109 connected to the lever 104 by a rod 110. The connection of the rod 110 to the lever is made discon- 105 nectable by means of a latch 111 to permit the independent operation of the lever and the parts connected thereto. The valves 96 110 and 108 are throttle valves and are manipulated when starting the engine. 110

The oil and air when introduced into the chambers 13 under a high pressure and in a diffused condition immediately explode. The 115 valves 15, working in proper sequences then open which permits the exploded gases to be directed into the pockets 11 which occurs each time one of the pockets passes each of the passageways 14. As there are three explosive chambers 13 and eight pockets 11 in the present instance, there will, therefore be twenty-four explosions or impulses on the rotor 9 on each revolution which makes a continuous turning movement. The burnt 125 gases exhaust out of the pockets 11 through the passageways 52 and through the valves 54 into the chambers 53. Water is then introduced into the chambers 53 which creates steam under a higher pressure than the ex- 130

haust gases. The valves 70 are then opened and properly turned to permit the passageways 69 to impinge the expanding steam into one of the buckets 67 of the rotor 10. 5 The exhaust steam subsequently passes out of the engine through chambers 81 into the pan 82.

Having described my invention, I claim:

1. In a rotary engine, a stationary casing 10 having explosive and exhaust chambers therein with passageways communicating therewith, a rotor having peripheral pockets mounted in said casing and receiving the impelling impacts from the explosions occurring in said explosive chambers, valves actuated from the rotor controlling the passageways communicating with said explosive chambers, governable valves actuated from said rotor and adapted to admit under 20 high pressure and in a diffused condition air and an explosive agent into said explosive chambers, and valves actuated from the rotor and controlling the passageways and the exhaust chambers communicating therewith.
2. In a rotary engine, a stationary casing 25 having explosive chambers and exhaust chambers with passageways communicating therefrom to the inner periphery of the said casing, a rotor having peripheral pockets 30 adapted to register with the said passageways, valves actuated from said rotor and controlling the passageways from the said explosive chambers, valves actuated from said rotor and controlling the passageways 35 of the exhaust chambers, and valves actuated from said rotor and controlling the admission of water to the said exhaust chambers concurrently with the exhaust thereto.
3. In a rotary engine, a stationary casing 40 having two divisions and explosive and exhaust chambers with individual passageways communicating therewith, a rotor mounted in one of said divisions having pockets adapted to register with said explosive and exhaust chambers, valves actuated from said 45 rotor controlling the passageways from the said explosive chambers to said pockets, valves actuated from said rotor for admitting air and fuel to said 50 explosive chambers under a condition of high pressure, valves actuated from said rotor and controlling said exhaust passageways and chambers, valves controlled by said rotor adapted to admit water to the 55 said exhaust chambers for the generation of steam therein, a second rotor in the other division of said casing having peripheral pockets, and valves actuated from the first named rotor controlling the admis-

sion of steam to the pockets of the second 60 rotor.

4. In a rotary engine, a stationary housing having explosive and exhaust chambers with individual passageways communicating therewith and additional exhaust 65 chambers with passageways communicating therewith, a rotor in said housing having peripheral pockets adapted to register with said passageways, valves controlling the passageways from the explosive chambers, 70 valves controlling the admission of air and fuel to the said explosive chambers, valves controlling the passageways of the first named exhaust chambers, a second rotor in 75 said housing having peripheral pockets adapted to register with the first named exhaust chambers and the said additional exhaust chambers, valves controlling the admission of steam from the first named exhaust chambers to the pockets in said second rotor, means for actuating all of said valves independently, and a common member actuated from the first named rotor and adapted to actuate in turn said independent valve actuating means. 85

5. In a rotary engine, a stationary housing having explosive chambers and combined exhaust and steam generating chambers with individual passageways communicating therewith, and steam exhaust chambers having individual passageways, a rotor in said housing having peripheral pockets adapted to register with the passageways of said explosive chambers and said combined exhaust and steam generating chambers, 90 valves controlling the passageways of the said explosive chambers, valves controlling the admission of air and fuel to the said explosive chambers, valves controlling the admitting water to the said combined exhaust and steam generating chambers, valves admitting water to the said combined exhaust and steam generating chambers, a second rotor in said housing having peripheral pockets adapted to register with the combined exhaust and steam generating chambers and the said steam exhaust chambers, valves controlling the admission of steam from said combined exhaust and steam generating chambers to the pockets in the second rotor, means for actuating all of said valves independently and at predetermined times, and a common cam member actuated from the first named rotor and in turn actuating all of the said valve operating means. 115

In testimony whereof I affix my signature.

EDWARD A. STEWART.
